United States Patent Office.

FREDERICK SHALLER, OF HUDSON, NEW YORK.

Letters Patent No. 101,927, dated April 12, 1870.

IMPROVEMENT IN COUPLINGS FOR HOSE AND PIPES.

The Schedule referred to in these Letters Patent and making part of the same

To all whom it may concern:

Be it known that I, FREDERICK SHALLER, of Hudson, in the county of Columbia and State of New York, have invented a new and useful Improvement in Hose or Pipe-Coupling; and I do hereby declare that the following is a full, clear, and exact description of the same, reference being had to the accompanying drawing forming part of this specification, and in which—

Figure 1 represents a longitudinal side elevation of my invention;

Figure 2 is a longitudinal section of the same, corresponding with fig. 1;

Figure 3 is a sectional face view; and

Figure 4 is a view of one end of my coupling.

Similar letters of reference indicate corresponding parts in the several figures.

This invention relates more especially to the coupling of flexible pipes, the ends of which are provided with flanges; and

It consists in making the coupling out of two bars, one of which is made in two parts, which part in the middle and are united by a hinge at one end, whereby it is enabled to be passed over the flange of the pipe. The pin which forms the pivot of said hinge also serves to unite the two bars at one end, while the other ends of the bars are secured by means which will be hereinafter described.

To enable others skilled in the art to construct hose or pipe-couplings in accordance with my invention, I will proceed to describe the same with reference to the drawing.

A A' are hose or pipes to be connected, which are provided with flanges a a' at their ends.

B B' are bars which form the coupling.

The bar B is made with an opening, b, and recess c in the middle, to enable it to be passed over the pipe A, and allow the flange a to rest in the recess c.

One end of this bar is provided with a slotted tail-piece, d, while the other end is provided with cheeks e e'.

The bar B' is made of two parts, which are hinged at one end and allowed to come apart in the middle, whereby it is enabled to be passed over the flange a', and clamps the pipe A' behind said flange.

C is a tightening-screw, which also serves the purpose of uniting the two bars B B'.

Said tightening-screw is pivoted to the slotted tail-piece d of the bar B, and, passing through the hinged portion of the bar B', also forms the pin for said hinge, and is secured by means of a nut, f.

D is another tightening-screw, which is passed through the hinged bridge g, at the opposite ends of the bars B B'.

The bridge g is hinged at one end to one of the cheeks e of the bar B, while the other end is rigidly held by a slotted brace, h, which may be hinged, as shown in the drawing, or it may be a spring, one end of which is fastened to the side of the bar B, alongside of one of the cheeks e, while the other end is provided with a slot, i, to enable it to be slipped over the end of the bridge g, and thereby hold it securely fast.

To enable the tightening-screw D to act on both parts of the bar B' which are passed between the cheeks e e' of the bar B, a strip, j, is fastened to one of those parts and made to lap over the other, forming a step for the tightening-screw D.

Now it will be seen that when the bars of the coupling are slipped over the pipes to be connected, they will bear against their respective flanges a a', and by operating the tightening-screws C D, can be forced easily together, to form a sufficiently tight joint.

Instead of the tightening-screw D, bridge g, and brace h, a wedge-shaped key passing through the cheeks e e' on the ends of the bar B', may be applied with the same effect.

What is here claimed, and desired to be secured by Letters Patent, is—

1. The combination of the bars B B', tightening-screw C, and nut f, substantially as and for the purpose herein described.

2. The tightening-screw D, bridge g, brace h, cheeks e e', and strip j, in combination with the bars B B', tightening-screw C, and nut f, substantially as and for the purpose herein set forth.

Witnesses: FREDERICK SHALLER.
